UNITED STATES PATENT OFFICE.

AXEL W. PETERSON, OF SAN FRANCISCO, CALIFORNIA, ASSIGNOR TO WESTERN TOOL AND WRENCH COMPANY, A CORPORATION OF CALIFORNIA.

CAN OPENER.

Application filed February 9, 1926. Serial No. 87,127.

The general object of the invention is to provide a can opener that may be used with safety in cutting the metallic end wall of a can and without liability from the cut edge 5 of the end wall inflicting injury to the hand of the operator.

Another object is to provide a can opener that may be operated to cut the end wall of a can with a minimum of effort on the part 10 of the operator and to effect the cutting expeditiously and neatly.

The above and other objects are accomplished by instrumentalities pointed out in the following specification.

15 The invention is clearly defined in the claims.

A satisfactory embodiment of the invention is illustrated in the accompanying drawings forming part of the specification 20 and in which

Figure 1 is a perspective of the invention in use.

Figure 2 is a detail plan view of the connected end portions of the operating levers 25 showing the cutter and means for advancing the cutter through the end wall of a can, a fragment of which is also shown.

Figure 3 is a detail cross-section on the line 3—3 of Figure 2, looking in the direction of the arrows.

Figure 4 is a view similar to Figure 3, but taken on the line 4—4 of Figure 2, and looking in the direction of the arrows, and

Figure 5 is a detail perspective of the cutting blade.

The device of the present invention is usable in connection with cans of various shapes. For purposes of illustration, I have shown a round can 5 of ordinary construction and the device of the present invention used in connection therewith. The top end wall 6 of can 5 is operated upon by forcing therethrough the pointed blade 7 of the present invention. As will be noted by 40 referring to Figures 3 and 5, the blade 7 is adapted to readily penetrate the metal of end wall 6 under relatively light pressure.

It will be noted by reference to Figure 2 that the blade 7 is inserted adjacent to the 45 peripheral portion of top end wall 6, and one of the side cutting edges 8 of the blade is provided with a reentrant cutting edge in the form of a notch 9 which is at the upper

end portion of the blade 7 when in use and arranged so as to operate directly upon the 55 metal of end wall 6.

The provision of the portion 9 aids in preventing vertical displacement of the blade 7 when in use. Blade 7 is advanced through the metal of the end wall 6 by a 60 substantially circular extension 10, the periphery of which is notched so as to provide a series of teeth 11 which are adapted to successively bite into the upper end portion of the side wall of the can when the extension 10 is turned in one direction.

The upper edge portion of the side wall of the can 5 is held rigidly between the extension 10 and blade 11 by lateral pressure applied thereto in opposed directions by a 70 pair of manually operable levers 12 and 13. One end portion of lever 12 is rigidly secured to extension 10 in any preferred manner.

Figure 1 is a perspective of the invention in use. In the form illustrated, extension 10 is 75 provided with a radial recess for the reception of the inner end portion of lever 12 so that when the lever is turned in either direction movement is imparted to extension 10. The lever 13 may correspond in construction to lever 12, and blade 7 has an offset end portion 14 which is rigidly secured to the inner end portion of lever 13 in any suitable manner as by a clamp screw 15.

The inner end portions of the levers 12 and 13 are connected by a link 16 which is pivotally connected to the inner portion of lever 13 beyond blade 7 and to the central portion of extension 10. The link is so proportioned in length that the extension 10 and 80 middle portion of the blade 7 are substantially opposite one another, and the end portion of the link connected to the lever 13 is offset upwardly as shown in the drawings and indicated by 17, so that the extension 10 and lever 12 are slightly below the horizontal plane of lever 13 when the device is in use, as shown in Figures 1, 2 and 4 of the drawings.

The provision of the link connection 100 serves to enable the device to be adjusted to can walls of various thicknesses and without materially changing the relative positions of the extension 10 and blade when the device is in use. The levers 12 and 13 may be provided with suitable handle portions 18 and 105

19 to provide convenient hand holds for the operator.

In using the device, blade 7 is forced into the upper end wall of the can and lever 18 moved so as to effect contact between the teeth 11 of extension 10 and the upper edge portion of the side wall of the can. Hand pressure tending to move the levers relative and toward each other is then applied by 10 grasping the handholds 18 and 19, whereupon extension 10 turns upon the adjacent portion of the side wall of the can which is braced against bending by the outward pressure applied thereto from blade 7. This 15 action causes the cutting edge of the portion 9 of the blade to cut the metal of the top wall 6 until the handholds 18 and 19 are relatively close together, whereupon lever 12 is turned outwardly and away from lever 13 and then turned the opposite direction 20 toward lever 13. This oscillating movement on the part of the lever 12 causes the blade 8 to cut the end wall 6 during the movement of lever 12 toward lever 13.

25 From the foregoing it is to be observed that the device of the present invention is comparatively simple in construction and inexpensive to manufacture. The provision of lever 12 provides ample leverage for causing the cutting of the end wall by the blade with little effort. It is to be noted that with the use of the present device, the operator is not required to use either hand in holding the can, in fact, the can is caused to turn in 30 a direction opposite from the direction of movement of the blade and the cutting of the top wall when the levers 12 and 13 are moved relatively and toward each other.

Although I have shown and described one 40 embodiment of my invention, it is to be understood that the same is susceptible of various changes; and I reserve the right to use such as may come within the scope of the appended claims.

45 I claim:

1. A can opener comprising a cutting blade adapted to penetrate the end wall of a can adjacent the periphery thereof and means for operating said blade to cut the end wall on a continuous line extending around the end wall from one end of a perforation made therein by the blade to the other end of the perforation, said means comprising a pair of relatively movable 50 manually operable levers, a link connecting said levers together at one end, one of said levers being rigidly secured to the blade and the other having its connected end portion provided with a curved extension having a 55 roughened surface adapted to bear upon the upper end portion of the side wall of the can at right angles to the blade and cooperate with the blade to grip said side wall therebetween when the said levers are moved 60 relatively toward each other whereby the 65

curved extension is caused to turn upon the side wall and advance the blade through the end wall.

2. A can opener comprising a cutting blade adapted to penetrate the end wall of a can adjacent the periphery thereof and means for operating said blade to cut the end wall along a continuous line extending around the end wall from one end of a perforation made therein by the blade to the other end of the perforation, said means comprising a pair of relatively movable manually operable levers, and a link connecting said levers together at one end, one of said levers being rigidly secured to the blade and the other having its connected end portion provided with an extension having a roughened surface adapted to bear upon the upper end portion of the side wall of the can at right angles to the blade and disposed so as to cooperate with the blade to grip the said side wall therebetween when the said levers are moved relatively toward each other, whereby the extension is caused to move the can in one direction and to advance the blade to move in an opposite direction through the end wall of the can.

3. A can opener comprising a cutting blade adapted to penetrate the end wall of the can adjacent to the periphery thereof, and means for operating said blade to cut the end wall along a continuous line extending around the end wall from one end of a perforation therein made by the blade to the other end of the perforation, said means comprising a pair of relatively movable manually operable levers, a link pivotally connecting the levers together at one end and having an offset end portion for disposing said levers to extend in parallel planes one above the other, one of said levers being rigidly connected to the blade and disposed at right angles thereto and the other having its connected end portion provided with an extension having a roughened surface adapted to bear upon the upper portion of the side wall of the can at right angles to the blade and cooperate with the blade to grip the said side wall therebetween when the said levers are moved relatively toward each other, whereby the said extension causes the can to move in one direction and the blade to move in an opposite direction through the end wall of the can.

4. In a can opener, a pair of levers, a link connecting said levers together at one end and permitting the levers to be oscillated one relatively to the other, a blade rigidly secured to one of said levers and extending at right angles thereto and having one of its cutting edges provided with a notch forming an inward extension of the cutting edge of the blade the other of said levers having an extension at its con-

nected end portion provided with a roughened surface and disposed opposite to the blade.

5. In a can opener, a pair of levers, means permitting the levers to be connected together at one end and adapted to be oscillated one relatively to the other, a blade rigidly secured directly to one of said levers and extending at right angles thereto and having one of its cutting edges provided with a notch forming an inward extension of the cutting edge of the blade, the other of said levers having a rounded extension peripherally provided with a toothed surface disposed

15 opposite to the blade.

6. A can opener adapted for cutting the peripheral portions of an end wall of a

can and comprising a pair of levers, one of said levers having directly connected thereto a blade provided with a cutting edge disposed at right angles to the lever, an element carried by the other of said levers and having a rounded roughened edge disposed at right angles to the cutting edge of the blade, a connection between the levers 20 adapted for permitting the roughened edge of the said element to turn in one direction and thereby turn a can and feed the peripheral portion of an end wall thereof to the blade when the blade is caused to penetrate the end wall of the can and the levers 25 moved relatively toward each other.

AXEL W. PETERSON.
